US00D566404S

(12) United States Design Patent (10) Patent No.: US D566,404 S
 (45) Date of Patent: * Apr. 15, 2008

(54) NON-WOVEN TEXTILE(75) Inventor: Gregory P. Harkenrider, Thornton, CO (US)(73) Assignee: Hunter Douglas Inc., Upper Saddle River, NJ (US)() Term: 14 Years(21) Appl. No.: 29/287,661(22) Filed: Sep. 5, 2007*Related U.S. Application Data

(60) Continuation of application No. 29/269,840, filed on Dec. 11, 2006, now Pat. No. Des. 554,870, which is a continuation of application No. 29/263,987, filed on Aug. 2, 2006, now Pat. No. Des. 536,533, which is a continuation of application No. 29/255,349, filed on Mar. 8, 2006, now Pat. No. Des. 530,101, which is a division of application No. 29/226,182, filed on Mar. 25, 2005, now Pat. No. Des. 521,744.

(51) LOC (8) Cl. ..... 05-05(52) U.S. Cl. D5/60

(58) Field of Classification Search ..... D5/1, D5/2, 3, 5, 7, 8, 11, 13, 14, 15, 16, 18, 19, D5/20, 23, 24, 25, 26, 27, 28, 30, 31, 32, D5/35, 36, 37, 39, 43, 45, 46, 47, 49, 50, D5/52, 53, 54, 55, 56, 57, 58, 59, 60, 61, D5/62, 63, 64, 65, 66, 99; D2/749, 984; D6/582, 583, 595, 596, 598, 603, 604, 605, D6/606, 608, 613, 616, 617, 619, 622; 428/17, 428/18, 151, 154, 156, 171, 187, 198, 199, 428/540, 542.2, 542.6, 904.4, 919; D24/124, D24/125; D25/142, 152; 5/413 AM, 709; 162/134, 140, 231; 156/148, 209; D7/396.4, D7/396.5
